US0D1056044S

(12) **United States Design Patent** (10) **Patent No.:** **US D1,056,044 S**
(45) **Date of Patent:** **** Dec. 31, 2024**

(54) **PRINTER FOR COILED MATERIAL**

(71) Applicant: **Procolored Technology Inc**, Pico Rivera (CA)

(72) Inventor: **Jiangyu Wu**, Shenzhen (CN)

(73) Assignee: **Procolored Technology Inc**, Pico Rivera, CA (US)

(**) Term: **15 Years**

(21) Appl. No.: **29/909,267**

(22) Filed: **Aug. 3, 2023**

(30) **Foreign Application Priority Data**

Apr. 26, 2023 (CN) 202330237896.5

(51) **LOC (14) Cl.** **18-02**

(52) **U.S. Cl.**

USPC **D18/53**

(58) **Field of Classification Search**

USPC D18/16, 19, 36, 39, 40, 50, 53, 56; D15/122, 135, 138, 144, 145, 146;

(57) **CLAIM**

The ornamental design for a printer for coiled material as shown and described.

DESCRIPTION

FIG. 1 is a perspective view of a printer for coiled material showing my new design;

FIG. 2 is a front view thereof;

FIG. 3 is an enlarged right view thereof;

FIG. 4 is an enlarged left view thereof;

FIG. 5 is a back view thereof;

FIG. 6 is a bottom view thereof;

FIG. 7 is a top view thereof;

FIG. 8 is an enlarged view of the encircled area 8 of FIG. 1;

FIG. 9 is an enlarged view of the encircled area 9 of FIG. 1;

FIG. 10 is an enlarged view of the encircled area 10 of FIG. 4; and,

FIG. 11 is an enlarged view of the encircled area 11 of FIG. 5.

The broken lines shown on the drawings depict portions of the printer for coiled material that form no part of the claimed design. The dot-dash-dot broken lines depict the enlarged view boundaries that form no part of the claimed design.

1 Claim, 11 Drawing Sheets
